UNITED STATES PATENT OFFICE.

GEORGE L. SMITH AND DORSEY F. ASBURY, OF WASHINGTON, DISTRICT OF COLUMBIA.

TANK CLOSURE.

1,420,063.

Specification of Letters Patent. Patented June 20, 1922.

Application filed August 16, 1920. Serial No. 403,872.

To all whom it may concern:

Be it known that we, GEORGE L. SMITH and DORSEY F. ASBURY, citizens of the United States, and residents of Washington, 5 in the District of Columbia, have invented certain new and useful Improvements in Tank Closures, of which the following is a specification.

Our invention relates broadly to tank 10 closures and is particularly adapted for use in connection with powder tanks.

The objects of our invention are to provide a closure in which the cover is forced into engagement with a sealing ledge 15 through the medium of the coaction between a wedging surface and an expansible split ring, which latter can be either one which is manually expanded or one which is expanded by its own resiliency; to provide a 20 closure of the type referred to wherein the split ring is corrugated parallel to its radii to materially reduce the area of contact between the ring and cover and thereby eliminate friction and the possibility of sticking 25 due to corrosion, and also providing a structure of locking ring which tends to effect equalization of pressure on all points of the gasket; to provide a closure embodying a top ring formed with exterior and interior 30 circumscribing grooves and ribs which permits interfitting of the tanks when stored in horizontal position to prevent relative movement between adjacent tanks, and which also permits one of the walls of an interior 35 groove to be utilized as a wedging surface for coaction with the expansible locking ring and the walls of the exterior groove to serve as a protection against damage to such interior groove by blows due to rough handling, and to provide a closure which will 40 be simple and efficient, relatively cheap to manufacture and easily applied and removed.

In the drawings chosen to illustrate our 45 invention the scope whereof is set forth in the claims:

Fig. 1 is a plan view of a powder tank closure constructed in accordance with our invention;

50 Fig. 2, a side view of what is shown in Fig. 1 partly in section, a fragmental section of the closure of an adjacent tank being also shown; and

55 Fig. 3, a section on the line 3—3 of Fig. 1. Referring to the drawing 1 represents the cylindrical part of a metal tank or container

and 2 the top ring secured to the tank body by riveting, welding or other suitable method. 3 indicates a bead formed by rolling over the upper edge of the cylindrical 60 part 1 and serves as a sealing ledge for the gasket 4 provided in the cover of the tank. The top ring 2 is provided with circumscripting flutes or corrugations 5 which serve as indicated at A in Fig. 2 to interlock a 65 series of tanks when stacked one upon another with their axes in a horizontal position. The cover 6 is provided with a gasket 4 preferably of rubber which engages the bead 3. A handle 7 is secured to the cover 70 for convenience in removing same. A split ring 9 is provided as a simple means for locking the cover in place and is movably secured to the cover by the clips 8. The free ends of the split ring 9 are provided 75 with an expander 12 pivoted at 13 to the end 10 and engageable with teeth 14 on the end 11. The split ring 9 is slightly crimped or corrugated as indicated at 9' in Fig. 2, so that the area of contact of this ring with the 80 cover and the top ring 2 is reduced to a minimum to reduce friction and possibility of sticking due to corrosion. This construction of the locking ring also tends to effect equalization of pressure on all points of the 85 gasket. The outer edge of the split ring 9, when expanded, presses against the corrugation 15 of the top ring 2 and a wedging action is set up which forces the ring down against the outer edge of the cover. The 90 free diameter of the split ring 9 is equal to the diameter of the cover 6 so that withdrawal of the cover is possible when the same is unlocked. Any expansion of the split ring increases its diameter and when 95 the cover is in position, its action against the downwardly inclined wall of the corrugation 15 of the top ring 2 effects a seal by producing pressure of the gasket 4 against the bead 3. The expander 12 is provided 100 with a toe 16 engageable with the inner circumference 17 of the split ring to limit rotation about the pivot 13 to an amount only sufficient to disengage the teeth 14. Its opposite end is provided with a toe 18 to act 105 as a fulcrum in expanding the split ring. This expansion is accomplished by a pinch bar or screw-driver 19 as shown in Fig. 1. With its end seated against one of the teeth 14, pressure on the implement in the direction of the arrow in Figure 1 will cause 110 pressure to be exerted on the toe 18 and ex-

pansion of the split ring can be effected tooth by tooth. It will also be seen that leverage exerted under the toe 18 will dis-
5 engage the teeth and allow the split ring to spring back to its free diameter, thus re-
leasing the cover for removal.

While it will be seen that we have illus-
10 trated and described a split ring of such free
diameter as to permit withdrawal of the
cover and which requires to be manually
expanded to effect a seal, it will be readily
understood that for certain conditions it
15 might be desirable to reverse the conditions
by providing a split ring of larger diameter
than that of the wedging surface so that it
would exert a radial pressure, and thus ef-
fect a seal, due to its own resiliency, with-
drawal being effected by reversing the ac-
20 tion of the expander and the engaging teeth
25 to permit manual contraction of the split
ring to such diameter as will permit removal
of the cover. Therefore when we use the
expression "an expansible split locking ring"
in the claims it is with the intent that such
30 expression will cover a split ring which is
expanded manually and contracted by its
own resiliency or split ring which is ex-
panded by its own resiliency and contracted
manually.

30 We claim:—

1. In a tank closure, the combination of a tank body having a wedging surface and a sealing ledge, a cover coacting with the sealing ledge, and an expansible split locking

ring coacting with the wedging surface and 35 cover during expansion and when ex-
panded, said ring having the faces thereof
which coact with the wedging surface and
cover provided with radial mating corruga-
tions whereby said ring during expansion 40
and when expanded will exert substantially
uniform downward pressure of the cover
against the sealing ledge throughout its en-
tire surface.

2. In a tank, the combination of a tank 45
body having a wedging surface and a seal-
ing ledge, an expansible split locking ring
coacting with the wedging surface during
expansion and when expanded to force the
cover against the sealing ledge, said ring 50
having its inner periphery adjacent one end
provided with teeth, a toothed pawl pivoted
to the other end of the ring and cooperating
with the teeth on the ring to lock the latter in
an expanded position, and a longitudinal ex-
tension on the free end of the pawl consti-
tuting a fulcrum for a tool engaged with
the ring teeth in the operation of manually
expanding the ring. 55

In testimony whereof we hereunto affix 60
our signatures in the presence of two wit-
nesses.

GEORGE L. SMITH.
DORSEY F. ASBURY.
